SLIDING WINDOW

Emil Munkert, Esslingen-on-the-Neckar, Wurtemberg, Germany, assignor to Fritz Hopmeier, Stuttgart, Wurtemberg, Germany

Application February 24, 1932, Serial No. 594,914,
and in Germany February 14, 1931

6 Claims. (Cl. 20—42)

I have filed applications in Germany Feb. 14, 1931, and Switzerland Feb. 17, 1931.

This invention refers to improvements in or relating to windows.

5 According to the invention there is provided a window wherein the weight of a pair of sashes is counterbalanced, and the object is that the counterbalancing means shall act upon the upper sash by being suspended from pivoted lever 10 means associated with the said sash, in such a manner that upon movement of the upper sash, the effective point of connection between the counterbalancing means and the upper sash is also moved.

15 Other features of the invention are hereinafter particularly described and set forth in the claims.

In order that the said invention may be clearly understood and readily carried into effect, the same will now be described more fully, by way of 20 example, with reference to the accompanying drawings, in which:—

Figure 1 is a longitudinal sectional view through the entire window construction,

Figure 2 is an end view of the window frame 25 showing the various parts corresponding to Figure 1,

Figure 3 is a longitudinal section of the window construction showing the window casements and in different positions than those shown in Fig- 30 use 1,

Figure 4 is an end view of the window frame showing the various moving parts in the positions corresponding to Figure 3, and

Figures 5 and 6 are end views of the window 35 frame showing the various moving parts in certain positions on an enlarged scale.

Referring to the drawings, the levers and the counterweights are placed within the boxes on both sides of the window frame *a*. The belt for 40 moving the casements is placed within the right-hand box. The casement *b* is pivoted at each side on a lever *c*, which lever is supported by a turnbolt. Another operating lever *e* (Figures 5 and 6) inside the box, corresponds with the lever 45 *c*, and is provided with a segment *f* of a cog-wheel which engages a cog-wheel segment *g* of the lever *h*. The lever *h* is pivoted at one end by means of a bolt *i* and at its free end supports a pulley *k* for carrying a wire or the like.

50 The upper casement is also pivoted on a lever *l* turning in a bearing disposed on the frame of the window. The lower casement *m* is guided as usual by a bolt or the like projecting into a vertical groove of the window frame. The weight of 55 the lower casement *m* is compensated at both

sides of the pane by a wire *n* and by the counterweight *o* being within the box. The wire *n* is fixed on the lower rail of the lower casement *m*, runs upwardly along this casement within the window frame and is guided by a pulley *p*, the wire *n* then runs around a guiding pulley *q* placed at the top of the counterweight *o* and around a pulley *k* and finally it is led to the free end of the lever *e*, having started from this lever *e* and having passed the guiding pulleys *s* along the 60 outside of the window-box and along the back of the said box.

As clearly indicated on the drawing, the wire *n* is fastened to the lever *e* and it passes around pulleys *s* as indicated by *r*. The member *r* could 70 be a wire, but since a wire is not very easily

grasped by the hand in order to operate the window, it is advisable to provide the rope or strap section *r* as indicated, one end of which is secured to the lever *e* and the other end is 75 secured as indicated in back of the weight *o*. This makes it very easy to grip the member *r* in order to operate the window, and as clearly indicated the section *r* and the wire *n* are secured to the lever *e*.

The above described arrangement operates as 80 follows:

The two casements *b* and *m* of the window being closed the two levers *e* and *h* form nearly a straight line, see Figure 5, and the lever *c* is 85 parallel to the window frame. When the belt *r* is pulled, the ends of the levers *e* and *h* come together and the lever *c* forces the top of the window outside the lower edge of this casement serving as an axis or pivot point, see Figure 1. 90 In this position of the casement, the air will enter the room and leave it, but no rain, etc., can enter. In this position, the weight of the upper casement *b* is compensated for by the counterweight *o* which has moved downwardly 95 for a short distance during this action.

By pulling the belt *r* further, the two levers *e* and *h* will become nearly parallel and the upper casement will be pushed out of the groove and to a position outside the window frame by 100 the lever *l*. In this position the casement *b* is nearly parallel at a certain distance from the window frame, see Figure 3. Thus the used air can escape over the upper side and the pure air can flow into the room. The lower casement *m* may now be readily moved upwardly, its weight being completely compensated for by the counterweight *o*, so that it will remain in any position. In order to shut the upper casement it is only necessary to pull the belt *r* in 105 110

the opposite direction when the upper casement will move in the other direction to closed position within the plane of the window frame.

Having thus described my invention, what I claim as new therein and desire to secure by Letters Patent is:

1. A window construction, comprising a window frame; an upper and a lower window casement, the upper casement being supported in the frame by turnbolts and the lower casement being slidably supported in the frame; and a counterweight in the frame for both window casements, the point of influence of the counterweight being movable with the movement of the upper window.

15 2. A window construction, comprising a window frame; a pivoted window casement pivotally mounted in the frame; a sliding window frame slidably mounted in the frame; a counterweight in the frame for both casements; and means for connecting the casements with the counterweight so that each will be counterbalanced thereby.

25 3. A window construction, comprising a window frame; a window casement mounted in the frame; a plurality of levers for pivotally mounting said window casement in the frame; a second window slidably mounted in the frame; a counterweight in the frame for both casements; and means for connecting the casements with the counterweight so that each will be counterbalanced thereby.

4. A window construction according to claim 3, in which the means for connecting the casements with the counterweight includes an operating lever in the frame connected to and operating with one of the pivot levers of the first mentioned casement and a wire having one end secured to the operating lever and the other end to the second-mentioned window casement and intermediately to the counterweight.

80 5. A window construction, comprising a window frame; a window casement mounted in the frame; a plurality of levers for pivotally mounting said window casement in the frame; a second window slidably mounted in the frame; a counterweight in the frame for both casements; an operating lever in the frame secured to and movable with one of the levers of the first-mentioned window casement; a second lever in the frame operatively connected to the operating lever; and a wire having one end secured to the operating lever and the other end to the second-mentioned window casement, and intermediately to the counterweight, the second lever cooperating with the wire and comprising the point of influence of the counterweight.

90 6. A window construction according to claim 5, in which a belt is provided cooperating with the operating lever to open or close the first-mentioned window casement.
